UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,260,412.

Specification of Letters Patent. Patented Mar. 26, 1918.

Application filed September 22, 1916. Serial No. 121,561.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems, and more particularly to improvements in automatic or semi-automatic telephone exchanges.

It is the object of this invention to provide a new and improved arrangement for controlling selectively operable switching devices employed in automatic or semi-automatic telephone exchanges.

A reduction in cost of selector and connector switches employed in automatic and semi-automatic telephone exchanges, is attained, within certain limits, by increasing the capacity of the switches. It has been found, for instance, that a five hundred point switch, that is to say, a switch the terminal bank of which contains five hundred sets of terminals, may be advantageously used in automatic telephone systems.

In systems in which five hundred point switches are employed, the sending or controlling device, by means of which the setting of this switch is controlled, must be equipped with an arrangement to "translate" the impulses. This is necessary because in order to set up the called subscriber's number, which is given in accordance with the decimal numerical system of indication, the senders must be arranged in accordance with the same numerical system of indication. If the number of the called line is, for instance, 1537, then the operator in a semi-automatic exchange will depress sender keys 1, 5, 3 and 7 in the thousands, hundreds, tens and units rows of keys.

Assuming that the capacity of the exchange is ten thousand lines, each of the five hundred point selector switches must have access to all the lines through five hundred point connector switches. To this end the selector switches are equipped with five sets of brushes and the terminal bank of each of these switches is divided into five levels, each level being served by one of the brushes. Thus, through each level access may be had to two thousand lines.

Supposing that the traffic conditions are

such that one hundred trunks are sufficient to give service to two thousand lines, each level contains four groups of terminals, and in each of these groups twenty-five terminals are provided for these trunks. Taking the first level of one hundred terminals, the trunks leading from the first group are extended to connectors containing the line terminals of the subscribers' lines 0000 to 0499; the trunks leading from the second group are extended to connectors containing the line terminals 0500 to 0999; from the third group the trunks lead to connectors containing line terminals 1000 to 1499; and from the fourth group the trunks lead to connectors containing line terminals 1500 to 1999. If line No. 1537 is desired, the brush having access to the first level of terminals must be selected. In view of the fact, however, that the thousands key depressed was key 1 and this key being the second in the row after key 0 will usually cause the sending of two impulses, the sender apparatus must be so provided that although the No. 1 key is depressed, only one impulse will be sent out to select the first set of brushes. Furthermore, in view of the fact that the line 1537 terminates in a connector accessible through trunks terminating in the fourth row of the first level of terminals of the selector switch, and the hundreds key depressed was number 5; that is to say, adapted to cause the sending of six impulses, it will be necessary to "translate" these six impulses in such a manner as to cause the selector switch to take only four steps.

These translating arrangements must be permanent fixtures of the exchange, because it could not be left to the operator to calculate what kind of a numerical digit should be sent out, instead of the numerical digit representing the called subscriber's line.

In commercial telephone exchanges it may be necessary to control by means of the sending apparatus, not only selector switches of the above described type, but also selectively operable switching devices which must be set in accordance with the decimal indication of the called subscriber's line. It would be possible to provide a special sending device in addition to the one controlling, for instance, the five hundred point switches, for controlling these decimal switches. This, however, would be an expensive arrangement.

According to the main features of the present invention a sending device adapted to control switches arranged in accordance with another numerical designation than the decimal, and provided with translating means, may also be used for setting selectively operable switching devices which must be adjusted in accordance with decimal numerical indication. Or in other words this invention provides automatic means for causing a switch to move to a position corresponding in numerical designation to that of its actuated controlling means, such as a sender key, although the actuated key predetermines the sending of impulses bearing a different numerical designation.

In the drawings, Figure 1 represents a calling subscriber's station, and a selector switch by means of which the calling line may be extended; Fig. 2 represents the circuits of a selector switch adapted to be operated by impulses translated at the sending device; Fig. 3 represents selectively operable switching devices which may be reached through the selector shown in Fig. 1 and which must be set in accordance with the decimal numerical indication; and Fig. 4 represents an operator's sending or controlling device for the selectively operable switches of the system. To show the complete circuit, Fig. 3 should be placed to the right, and Fig. 4 below Fig. 1. Fig. 2 should be placed below Fig. 3.

Only so much is shown of the circuits and apparatus as is necessary for an understanding of the invention. A complete circuit arrangement for the selector switches shown in Figs. 1 and 2 may be had from Patent No. 1,168,319 to A. E. Lundell. These selector switches are preferably of the so-called panel type, and are similar in structure to the switch disclosed in Patent No. 1,123,696 to E. B. Craft and J. N. Reynolds.

Sequence switches 106, 212, 307 and 401, shown in Figs. 1, 2, 3 and 4 respectively, are similar to the switch structure described in Patent No. 1,127,808. The sequence switch contacts shown in Figs. 1, 2 and 4 and above the horizontal dotted line in Fig. 3, are controlled by the respective sequence switches, but for the sake of clearness, these contacts are indicated diagrammatically instead of in their structural relation to each other.

The selectively operable switching devices which must be set in accordance with the decimal indication of the called line are shown below the horizontal dotted line in Fig. 3. The sequence switches 308, 320, 309, 310 and 311 are of the same structure as the sequence switches above referred to, the contacts controlled by each of these switches being shown within the dotted rectangles in the lower part of Fig. 3. By means of these

switches the A operator whose sending device is shown in Fig. 4, may cause the indication of the number of a called line at a B operator's position. The lamps shown in the rectangle, including the contacts of switch 308, are lighted in the various positions of this switch. The hundreds, tens and units indicator switches 309, 310 and 311 control also lamps for indicating the number of the called line. Only one of the indicating lamps is shown adjacent to these latter mentioned switches, the location of the other lamps being merely indicated at contacts of such switches.

It will be obvious to those skilled in the art that instead of the disclosed translating arrangement, other translating arrangements may be used without departing from the spirit of the present invention. This would be necessitated, for instance, if other than five hundred point switches are used, or if it is desired to control the counting relays shown in Fig. 4 through so-called register controllers instead of directly by the keys. Patent No. 1,168,319 discloses such an arrangement. Patent No. 1,157,881 shows a translating arrangement for two hundred point switches. Obviously, if other translating arrangements are used, the arrangements of the contacts of the indicator switches shown in Fig. 3 must also be changed in accordance with the present invention. It will be further obvious that instead of the sending apparatus, the selector switches, the sequence switches and the number indicators described in the mentioned patents, apparatus of widely varying character may be employed without departing from the spirit of the present invention. Instead of indicator switches shown in Fig. 3 for instance, step-by-step one hundred or ten point switches may be employed.

A full understanding of the present invention may be had from the following detailed description and the appended claims.

A subscriber at station 100 desiring to initiate a call removes his receiver from the switchhook, whereupon relay LR becomes energized and causes the actuation of a calling lamp CL. An A operator, whose telephone head set is shown at 101, noticing the lamp CL lighted, inserts a plug 102 into an answering jack 103 in which the calling subscriber's line terminates. Relay SR becomes energized through the calling line circuit and a circuit is closed from ground, through the winding of a relay 104, the sleeve contacts of plug 102 and jack 103, and the winding of a cut-off relay CO to grounded battery. The cut-off relay disconnects the line relay, whereupon lamp CL is extinguished. Relay 104 closes a circuit from ground, through its armature and front contact, a contact 105 and the power magnet of a sequence switch 106 to grounded

battery, for moving this sequence switch out of position 1, and under the control of its normal spring 107 into position 2.

As soon as the sequence switch 106 reaches position 2 a circuit is established from ground, through a sequence switch contact 108, a conductor 109, a contact 400 of a sequence switch 401, and the winding of a relay 402 to grounded battery. Relay 10 402 closes a locking circuit for itself from grounded battery, through its winding, a sequence switch contact 403, the right-hand front contact and armature of relay 402, conductor 404 and a sequence switch contact 15 110 to ground. A circuit is also closed from ground, left-hand front contact and armature of relay 402, a contact 405 and the power magnet of sequence switch 401 to grounded battery, for moving this sequence 20 switch out of position 1 into position 3.

By depressing a listening-key 111 the operator connects her telephone set 101 into telephonic association with the calling subscriber, and having learned from him the 25 called subscriber's number, will set up such number on her keyboard, shown in Fig. 4. Let us assume that the calling subscriber desires to obtain a connection with a line associated with an office into which trunks 30 112, 113, 114 lead. As these trunks terminate in the first group of contacts of an office selector 115, the operator will depress an office key 406, having already moved the sequence switch 401 out of position 3 and into 35 position 4 by a circuit established through a start key 407 and a sequence switch contact 408.

In position 4 of sequence switch 401 a fundamental circuit is closed from ground 40 battery, through the winding of relay 116, sequence switch contact 117, conductor 118, sequence switch contact 409, the outer armature and back contact of the upper counting relay 0, the windings of a stepping 45 relay 410, conductor 411 and a sequence switch contact 119 to ground. Relay 116 closes a locking circuit for itself through its left-hand front contact and armature and a sequence switch contact 120. Relay 116 also 50 closes a circuit from ground, right-hand front contact and armature of relay 116, a sequence switch 121, a conductor 136 and the power magnet of sequence switch 106 to grounded battery. Sequence switch 106 55 moves into position 3 and closes a circuit from ground, through the right hand armature and front contact of relay 116, a contact 121, and the winding of an up-drive magnet 122 to grounded battery. By at- 60 tracting its armature, magnet 122 presses a brush rod 123 carrying wipers 124, 125, 126 and a commutator brush 128 against a roller 127 constantly rotating in the direction indicated by the arrow, whereupon the wipers 65 will be caused to move over a terminal bank

129, and the brush 128 over a commutator plate 131.

Relay 410 closes a circuit from ground through its armature and front contact, a sequence switch contact 412, the contact of 70 key 406, conductor 413, the winding of the lower counting relay 0, and a conductor 414 to grounded battery. Upon the energization of the lower counting relay 0 a circuit is closed from ground through a sequence switch 75 contact 415, the armature and front contact of the lower counting relay 0, and the windings of the upper and lower counting relays 0, and conductor 414 to grounded battery. Due to the shunt path closed from the winding of 80 the lower counting relay 0 at the armature and front contact of stepping relay 410, the upper counting relay 0 cannot become energized. As soon, however, as commutator brush 128 contacts with a conducting segment 85 130 of commutator plate 131, a shunt is closed around relay 410 from ground through brush 128, conducting segment 130, a conductor 132, and sequence switch contacts 133 and 120, to the winding of relay 90 116. The stepping relay 410 becomes de-energized and removes the short circuit from around the winding of the upper counting relay 0. The upper counting relay 0 then becomes energized and opens the funda- 95 mental circuit at its outer armature and back contact. It closes also a circuit from ground, through sequence switch contact 416, its inner armature and front contact, and the winding of the power magnet of sequence 100 switch 401 to grounded battery, for moving the sequence switch out of position 4 into position 6. While the sequence switch is moving from position 4 to position 6, the counting relays are unlocked. Upon the 105 opening of the fundamental circuit and as soon as brush 128 encounters an insulated segment 134, removing thus the ground from the winding of relay 116, this relay becomes deenergized, and assuming that the first 110 trunk in this group is idle, a circuit is closed from ground through the right-hand armature and back contact of relay 116, sequence switch contact 135, conductor 136, and the power magnet of sequence switch 106 to 115 grounded battery, for moving this sequence switch out of position 3 into position 11.

When sequence switch 106 reaches position 8 a circuit is closed from ground, through sequence switch contact 140, wiper 120 126, terminal 141, conductor 114, and the winding of a relay 200 to grounded battery. Relay 200 becomes energized and controls the guarding of trunk 112, 113, 114 in the well-known manner. When sequence switch 125 106 reaches position 11 and sequence switch 401 position 6, the fundamental circuit is extended for controlling a group selector switch 201.

Let us suppose that this exchange has a 130

capacity to accommodate ten thousand lines. Two hundred connector switches (not shown) to which the calling line may be extended through selector switch 201, will be provided, each of these connector switches containing the terminals of five hundred lines. The terminal bank 202 of the selector comprises five hundred sets of contacts in which trunks leading to the connector switches terminate. Each of the selector switches, fifty of such switches being provided for a ten-thousand line exchange, has an access to all the lines through the connectors.

15. The terminal bank of the selector 201 is divided into five levels (only a few of the levels being shown) each containing one hundred terminals, in which terminate a sufficient number of trunks, preferably one hundred in each, for accommodating the traffic with two thousand lines to which access may be had through each of these levels of terminals. In order to make possible the seizure of a set of terminals in any 20 one of the selector terminal levels, five sets of brushes 203, 204, 205, 206, 207 are provided on a brush rod 201, of the selector. Supposing that the called subscriber's number is 1537, the operator after having controlled the setting of the office selector 115, depresses key No. 1 in the thousands, key No. 5 in the hundreds, key No. 3 in the tens, and key No. 7 in the units rows of keys.

30. The first of the connectors has access to the subscribers' lines Nos. 0000-0499, and the fourth connector has access to lines 1500-1999. The four connectors serving lines 0000-1999 may be reached through the twenty-five trunks terminating in the first 35 group of the terminal bank 202. It will be necessary therefore to operate or trip brushes 203 and to cause them to perform four steps. In view of the fact that the operator depressed the thousands key No. 1 and the hundreds key No. 5, it is necessary that the two and six impulses which would be usually received by the counting relays upon the depression of similar keys, be "translated" into one and four impulses. 40. This "translation" is accomplished by wiring the thousands and hundreds keys in a manner shown in Fig. 4 of the drawings.

45. The left-hand contacts 420 and 421 of the thousands keys 0 and 1 are wired to the 0 counting relays; that is to say, no matter whether 0 or 1 is the thousands designation of the called line, the first set of brushes will be selected, because these are the brushes that may select trunks leading to 50 connectors in which the subscribers' lines from 0000 to 1999 terminate. In a similar manner the left-hand contacts of the thousands keys 2, 3; 4, 5; 6, 7; and 8, 9 are wired to counting relays 1, 2, 3 and 4 respectively. 60. The right-hand contact 422 of the thousands

key No. 0 is wired to the hundreds keys in one row with key 424. The right-hand contact 423 of the thousands key No. 1 is wired to the hundreds keys in one row with key 425. Similarly the right-hand contacts of the even number thousands keys are wired to the hundreds keys in one row with key 424, and the right-hand contacts of the odd number thousands keys are wired to the hundreds keys in one row with key 425. 70 The contacts of the hundreds keys 0 to 4 in one row with key 424 are wired to the counting relays 0, and the contacts of keys 5-9 in this row are wired to counting relays 1. The contacts of the hundreds keys 0 to 4 in one row with key 425 are wired to counting relays 2, and the contacts of keys 5 to 9 in this row to counting relays 3. The contacts of the hundreds keys in one row with key 426 are wired as follows: keys 0 and 5 to No. 0, keys 1 and 6 to No. 1, keys 2 and 7 to No. 2, keys 3 and 8 to No. 3, and keys 4 and 9 to No. 4, counting relays. The tens and units keys are wired in numerical order to the counting relays. 80

90. The fundamental circuit above referred to may be traced as follows: from grounded battery, through the winding of a relay 210, a contact 211 of a sequence switch 212, conductor 112, terminal 142, wiper 124, a sequence switch contact 143, conductor 118, sequence switch contact 409, the outer armature and back contact of upper 0 counting relay, the windings of the stepping relay 410, conductor 411, a sequence switch contact 144, wiper 125, terminal 145, conductor 113 and sequence switch contact 213 to ground. Relays 210 and 410 become energized. By attracting its right-hand armature, relay 210 closes a locking circuit for itself. By 100 attracting its left-hand armature relay 210 closes a circuit from ground through its right-hand armature and front contact, a contact 214 and the power magnet of sequence switch 212 to grounded battery, for 105 moving this sequence switch out of position 1 and into position 2.

110. In position 2 of sequence switch 212 a circuit is closed from ground through the left-hand armature and front contact of relay 210, a sequence switch contact 215 and the winding of an up-drive magnet 216, to grounded battery. Under the control of the updrive magnet all the wipers of selector 210 and commutator brushes 217 and 218 115 are caused to travel in an upward direction. The brushes are normally held out of engagement with the contacts of terminals of bank 202, and before these brushes reach 120 in their travel a position below the first group of terminals of the level they serve, brush 217 engages a conducting segment 219.

125. Upon the energization of the stepping relay 410 a circuit is established from ground 130

through the front contact and armature of this relay, a sequence switch contact 427, conductor 428, contact 421 of the thousands key 1, conductor 429, the winding of the 5 lower counting relay 0 and conductor 414 to grounded battery. The lower counting relay 0 upon energization, closes a locking circuit through the windings of the upper and lower counting relays 0, the upper 10 counting relay 0 however, as it has been above explained, cannot become energized due to the shunt path closed at the front contact of stepping relay 410. As soon, however, as brush 217 connects ground 15 through conducting segment 219, a conductor 220 and sequence switch contacts 222 and 231 to the winding of relay 210, the stepping relay 410 is shunted out and permits the energization of the upper counting 20 relay 0. This relay by opening its outer contact causes the deenergization of relay 410 and closes through its inner contact a circuit for driving sequence switch 401 out of position 6 into position 8, causing thus 25 the unlocking of the counting relays.

When brush 217 is moved into engagement with an insulated segment of conducting segment 219, the circuit of relay 210 is broken and the magnet becomes deenergized. 30 Upon the deenergization of relay 210 a circuit is closed from ground through the left-hand armature and back contact of this relay, contact 223 and the power magnet of sequence switch 212, to grounded battery, for 35 moving this sequence switch out of position 2 into position 3. In this position of the sequence switch a circuit is closed from ground through a sequence switch contact 224 and the winding of a trip magnet 225 to grounded battery. This magnet becomes energized 40 and causes the rotation of a trip rod (not shown) by one step, whereby during the further movement of the brushes, brushes 203 will be tripped into engagement with the 45 contacts of the first level of the terminal bank. The tripped brushes are now in a position to engage the lowest terminals of the first level and the commutator brushes are in a position where brush 218 engages a conducting segment at 226. 50

In position 8 of sequence switch 401 and position 3 of sequence switch 212 the fundamental circuit is reestablished and relay 410 and 210 become again energized. Relay 210 55 closes a circuit through its right-hand armature to lock up its winding, and a circuit from ground through its left-hand armature and front contact, and a contact 214 and the power magnet of sequence switch 212 to grounded battery, for driving this sequence 60 switch out of position 3 into position 4. The relay 410 closes a circuit from ground, through its front contact and armature, sequence switch contact 430, conductor 431, 65 the contact 423 of the thousands key 1, con-

tact 432 of the hundreds key 5, conductor 433, the armature and back contact of the upper counting relay 3, the winding of the lower counting relay 3, and conductor 414 to grounded battery. The lower counting 70 relay upon energization, closes a locking circuit through sequence switch contact 415 and the windings of the upper and lower counting relays 3. The upper counting relay 3 cannot become energized due to the shunt 75 path closed at the front contact of the stepping relay 410. As soon, however, as brush 218 contacts with the conducting segment at 226 and connects thus ground through conductor 227 and sequence switch contacts 228 80 and 231 to the winding of relay 210, the stepping relay 410 becomes deenergized and removes the short-circuit from the winding of the upper counting relay 3, and this relay extends conductor 433 to the winding of the 85 lower counting relay 2. The operation of the counting relays continues until upon the engagement of the conducting segment at 230 by commutator brush 218, the stepping relay 410 is shunted the fourth time and the upper 90 counting relay 0 becomes energized. The sequence switch 401 is moved then out of position 8 into position 10, the relays 410 and 210 become deenergized, and the counting 95 relays are unlocked.

The brush 218 engages the conducting segment at 226 and 230 when the brushes 203 are just below the first and fourth groups of contacts in the terminal bank. As long, therefore, as the brush 218 engages 100 conducting segment 230, ground is connected through conductor 227 and sequence switch contacts 228 and 231, the right-hand armature, front contact and the winding of relay 210 to grounded battery, and this relay 105 remains locked up, although the fundamental circuit is open. As soon, however, as the brush 218 leaves the conducting segment and engages an insulated segment 230', this locking circuit is opened. Relay 210 110 becomes deenergized and closes a circuit through its left-hand armature and back contact, contact 223 and the power magnet of sequence switch 212 to grounded battery, for moving this sequence switch out of position 4. Magnets 225 and 216 become deenergized, whereupon the tripping spindle 115 is released to normal and the wipers 203 are stopped on the fourth row of terminals in the first group of bank 202.

Sequence switch 212 is moved from position 4 into position 16 under the control of a normal spring 212' and while moving through the intermediate positions, controls various circuits of selector 201, but in view 125 of the fact that the above description is deemed sufficient to enable one skilled in the art to understand the arrangement for controlling the translation of the impulses, these circuits have not been disclosed in detail. 130

Supposing that the first terminal in the fourth row is idle, the sequence switch 212 closes in position 8 a guarding circuit through sequence switch contact 232 for preventing the seizure of the selected trunk by other selector switches.

The connector switch (not shown) which has been seized by selector 201 is similar in construction to the latter. Upon the extension of the trunk 112, 113 to the trunk leading to such connector switch, the zero or first set of brushes of such connector will be selected, because in position 10 of the sequence switch 401 a circuit is closed from ground through the front contact and armature of relay 410, a sequence switch contact 435, conductor 436, contact 437 of the hundreds key 5, conductor 438 and the winding of the lower counting relay 0 to grounded battery. The trip magnet of the connector will move the tripping spindle (not shown) by one step. The reason for this is that the subscriber's line is in the lowest group of terminals of the connector switch. The connector is caused to seize the called subscriber's line in accordance with impulses predetermined by the tens and units keys in positions 12 and 14, of the sequence switch 401.

30 After the sending out of the last series of impulses sequence switch 401 is moved into position 1, in which position relay 402 becomes deenergized and a circuit is closed from ground through a sequence switch contact 440, a conductor 441, a contact 150 and the power magnet of sequence switch 106 to grounded battery, for moving this sequence switch out of position 11 into position 16. When the called subscriber answers, the 40 supervisory relay SR' becomes energized.

When disconnection is desired and both the calling and called subscribers cause the actuation of their respective supervisory relays, the A operator removes plug 102 from jack 103, causing the deenergization of relays CO and 104. A circuit is then closed from ground, through the armature and back contact of relay 104, a contact 151 and the power magnet of sequence switch 106 to 45 grounded battery, for moving this sequence switch out of position 16 into position 18. A circuit is then closed from ground through sequence switch contact 152 and the winding of a down-drive magnet 153 to grounded battery. This magnet becomes energized and by attracting its armature presses brush rod 103 against the roller 154 constantly rotating in the direction indicated by the arrow. The wipers and the brush 128 of the selector 50 115 are caused to travel in a downward direction, and when brush 128 engages a conducting segment 155, ground is connected through conductor 156, sequence switch contact 157, conductor 136, and the power magnet of sequence switch 106, to grounded battery. This

sequence switch is moved out of position 18 into position 1, whereupon magnet 153 becomes deenergized.

When wiper 126 leaves terminal 141, relay 200 becomes deenergized and closes a circuit from ground through its armature and back contact, a contact 240 and the power magnet of sequence switch 212 to grounded battery, for moving this sequence switch out of position 16 into position 18. A circuit is then closed from ground through sequence switch contact 241, and the winding of a down-drive magnet 242 to grounded battery. Under the control of this magnet the wipers and brushes of selector 201 are brought to their normal position. When brush 218 reaches its normal position a circuit is closed from ground through brush 218, a conducting segment 243, conductor 244, a contact 245 and the power magnet of sequence switch 212 to grounded battery, for driving this sequence switch out of position 18 into position 1, whereupon magnet 242 becomes deenergized. The connector is released in a similar manner upon the restoration of selector 201. Let us suppose that the calling subscriber at station 100 desires to obtain a connection with a subscriber located at station 300, the line of whom may be seized by a B operator whose position apparatus is shown in Fig. 3. The calling subscriber is associated with the A operator in the same manner as above described, but this operator causes the setting of selector 115 onto a trunk such as 160, 161, 162 leading to the office in 50 which the called line terminates, and terminating in a B operator's plug 301. The setting of selector 115 is accomplished in the same manner as above described with the difference that in order to set the switch 105 onto the desired terminal, the operator depresses the office key 450, causing the selector 115 to take two steps. After the setting of selector 115 the sequence switch 401 is moved into position 6, and sequence switch 106 is 55 standing in position 11, as above described. Upon the completed seizure of the trunk, a circuit is closed from grounded battery, through the winding of a relay 302, conductor 162, wiper 126 and sequence switch contact 140 to ground. Relay 302 becomes energized. Another circuit is closed from ground through a sequence switch contact 303, conductor 161, brush 125, sequence switch contact 144, conductor 411, the windings of stepping relay 410, the back contact and outer armature of the upper counting relay 0, sequence switch contact 409, conductor 118, sequence switch contact 143, wiper 124, conductor 160, conductor 316, sequence switch contact 304 and the winding of a relay 305 to grounded battery. This is the fundamental circuit. Relay 305 closes a locking circuit for itself through its left-hand armature and front contact, and a circuit 60

from ground through its right-hand armature and front contact, a contact 306 and the power magnet of sequence switch 307 to grounded battery, for moving this sequence switch out of position 1 and into position 2.

5 Supposing that the number of the line leading to station 300 is also 1537, the A operator depresses the same thousands, hundreds, tens and units keys as in the above assumed case.

10 Upon the depression of the thousands key 1 a circuit is closed from ground through the front contact and armature of stepping relay 410, sequence switch contact 427, conductor 428, contact 421 of the thousands key, conductor 429, the winding of the lower counting relay 0, and conductor 414 to grounded battery. The lower counting relay becomes energized and closes a locking circuit for the upper and lower counting relays 0, the former of which is shunted out by stepping relay 410.

15 In position 2 of sequence switch 307 a circuit is closed from grounded battery, through the power magnet of indicator 308, a sequence switch contact 312, and the right-hand front contact and armature of relay 305 to ground. Under the control of its normal spring 313, indicator 308 is moved from position to position 0. When it is moving through position N-1/2; that is to say, between positions N and 0, a circuit is closed from ground through indicator contact 314, sequence switch contact 315, conductor 316, and sequence switch contact 317 to the winding of relay 305, causing thus the shunting out of the stepping relay 410 in the same manner as has been described in connection with the selector switch 115.

20 Upon the deenergization of stepping relay 410 the upper counting relay 0 becomes energized. The fundamental circuit is then opened at the outer armature and back contact of the upper counting relay 0, resulting in the deenergization of relays 410 and 305. Relay 305 closes a circuit from ground through its right-hand armature and back contact, a contact 318 and the power magnet of sequence switch 307 to grounded battery, and under the control of its normal spring 319 this sequence switch is driven out of position 2 into position 3. The circuit of indicator 308 is then interrupted at contact 312, and this indicator stops in position 0.

25 The energization of the upper counting relay 0 causes also the movement of sequence switch 401 out of position 6 into position 8, and thus the unlocking of the counting relays. When the sequence switch 401 reaches position 8, the fundamental circuit is re-established, relay 305 locks up and closes through its right-hand front contact and sequence switch 306 a circuit for moving sequence switch 307 out of position 3 into position 4. A circuit is closed from ground-

ed battery through the power magnet of translator 320, sequence switch contact 322 and the right-hand front contact and armature of relay 305 to ground. Under the control of its normal spring 321 this translator 70 is moved from position to position.

Upon the reenergization of stepping relay 410 a circuit is closed from ground, through the front contact and armature of this relay, sequence switch 430, conductor 431, contact 423 of the thousands key, contact 432 of the hundreds key 5, conductor 433, the armature and back contact of the upper counting relay 3, the winding of the lower counting relay 3, and conductor 414 to grounded battery. The lower counting relay 3 becomes energized and the upper counting relay 3 remains shunted until translator 320 moves through position N-1/2 and shunts out the stepping relay 410 by 80 connecting ground through its contact 323, sequence switch contact 324, conductor 316, and sequence switch contact 317, to the winding of relay 305. The upper counting relay 3 then extends the circuit to the lower counting relay 2. The upper counting relay 2 becomes energized in position 0-1/2 and the upper counting relay 1 in position 1-1/2 of translator 309. The upper counting relay 0 energizes and opens the fundamental circuit 95 when translator 320 closes contact 323 in position 2-1/2 and deenergizes relay 410. When sequence switch 320 leaves position 2-1/2, relay 305 deenergizes and closes at its right-hand armature and back contact a circuit to move the sequence switch 307 out of position 4 and into position 5, and the translator 320 is arrested in position 3, its circuit being broken at 322.

30 Upon the reenergization of relay 305 sequence switch 307 is moved out of position 5 into position 6, in which position a circuit is established from grounded battery, through the power magnet of the hundreds indicator 309, a sequence switch contact 325, 100 and the right-hand front contact and armature of relay 305 to ground. Under the control of its normal spring 326, indicator 309 is moved from position to position.

35 The sequence switch 401 is driven out of position 8 into position 10, whereupon the fundamental circuit energizing relays 410 and 305 is re-established at the outer contact, upper relay 0, and a circuit is closed from ground through the front contact and armature of stepping relay 410, sequence switch contact 435, conductor 436, and contact 437 of the depressed hundreds key 5, conductor 438, the winding of the lower counting relay 0, and conductor 414 to grounded battery. 115

40 While switch 309 is moving through position N-1/2 ground is connected through indicator contact 327 and sequence switch contact 328 to conductor 316, resulting in the shunting out of stepping relay 410. The 120 125

upper counting relay 0 then becomes energized and moves the sequence switch 401 out of position 10 into position 12 and opens the fundamental circuit. Relays 410 and 305 become deenergized and the latter moves the sequence switch 307 out of position 6 into position 7. The hundreds indicator 309 stops in position 0.

The successive resting positions of indicator 309 are indicated above its master contact 326. It will be noted that these resting positions are numbered N, 0, 5, 1, 6, 2, 7, 3, 8, 4, 9. This irregular numbering of resting positions is necessitated by this; that when, e. g., the indicator is caused to move into its third resting position, not lamp No. 1, as is the case with the other indicator switches, but lamp No. 5 must be lighted.

In position 12 of the sequence switch 401 the fundamental circuit is reestablished, and relay 305 upon energization moves sequence switch 307 out of position 7 into position 8, and locks itself up through its left-hand armature. A circuit is then closed from ground through the right-hand armature and front contact of relay 305, sequence switch contact 330, and the power magnet of the tens indicator 310 to grounded battery. This indicator is moved out of position N, and under the control of its normal contact 331 moved from position to position. The stepping relay 410 establishes a circuit from ground through its front contact and armature, sequence switch contact 460, conductor 461, the tens key 3, conductor 462, the armature and back contact of the upper counting relay 3, the winding of the lower counting relay 3 and conductor 414 to grounded battery. The lower counting relay 3 prepares the circuit of the upper counting relay 3, and this counting relay becomes energized when indicator 310 shunts out the stepping relay 410 in position N-1/2 by connecting ground through its contact 332 and sequence switch contact 333 to conductor 316. In position 0-1/2 of the tens indicator, the upper counting relay 2 becomes energized; in position 1-1/2 the upper counting relay 1 and in position 2-1/2 the upper counting relay 0 becomes energized, moves the sequence switch 401 out of position 12 into position 14, and opens the fundamental circuit. Relays 410 and 305 become deenergized and the latter by moving sequence switch 307 out of position 8 and into position 9, causes the arresting of indicator 310 in position 3.

As soon as the indicator 310 reaches position 0, a circuit is closed from ground through a contact 334 of this indicator, a contact 335 of the translator 320, a contact 336 of the hundreds indicator 309 (this indicator being in position 0), and the power magnet of indicator 309 to grounded battery. The indicator 309 is thus moved out of position 0 and under the control of its

normal spring 326 into position 5, whereupon its circuit being open at contact 336 and the indicator stops. Another circuit is closed from ground through contact 334, a contact 370 of the translator 320 and a contact 371 and the power magnet of indicator 308. The thousands indicator will then be moved into position 1.

Upon the reestablishment of the fundamental circuit relays 305 and 410 become energized and sequence switch 307 is moved out of position 9 into position 10, whereupon a driving circuit is closed through sequence switch contact 337 for the units indicator 311. This indicator is moved out of position N and is controlled in its further movement by normal spring 338. Relay 410 closes a circuit through sequence switch contact 463 and the contact of the units key 7 for the lower counting relay 7, and this prepares the circuit of the upper counting relay 7. The upper counting relay 7 becomes energized when in position N-1/2, indicator 311 closes contact 339, extending thus a ground through sequence switch contact 340 to conductor 316, whereupon the stepping relay 410 is shunted. The upper counting relay 6 becomes energized in position 0-1/2; the upper counting relay 5 in position 1-1/2; the upper counting relay 4 in position 2-1/2; the upper counting relay 3 in position 3-1/2; the upper counting relay 2 in position 4-1/2; the upper counting relay 1 in position 5-1/2; and the upper counting relay 0 in position 6-1/2 of indicator 311. The energization of the upper counting relay 0 causes sequence switch 401 to move out of position 14 into position 1 and opens the fundamental circuit, whereupon relays 410 and 305 become deenergized and the latter by moving sequence switch 307 out of position 10 into position 11, causes the stopping of the units indicator in position 7.

Upon the movement of the sequence switch 401 into position 1, sequence switch 106 is moved out of position 11 into position 16.

In position 11 of sequence switch 307, ground is connected through sequence switch contact 341, contact 342 of the thousands indicator and a lamp 343 to grounded battery. Due to the closure of the same contact 341, lamps 344, 345 and 346 will also be lighted. The lighting of these lamps indicates to the B operator the number of the desired subscriber. She then inserts plug 301 into a multiple jack 347 of this subscriber, whereupon a circuit is established from grounded battery, through the winding of the cut-off relay CO₁ of the called line, the sleeve contacts of jack 347 and plug 301, and the winding of relay 348 to ground. Relay 348 closes a circuit from ground through its front contact and armature, a contact 349 and the power magnet of sequence switch 307 to grounded battery, 130

whereupon the sequence switch is moved out of position 11 into position 13. When the sequence switch 307 moves out of position 11 and opens contact 341, the lamps are extinguished, and as soon as the sequence switch reaches position 12 and closes its contacts 350, 351, 369, 352 and 353, the thousands, hundreds, tens and units indicators and the translator are restored to normal.

10 In position 13 of sequence switch 307 a circuit is closed from ground through a ringing generator 355, a ringing relay 358, sequence switch contact 356, the called line circuit and sequence switch contact 357 to ground. When the called subscriber answers, relay 358 becomes deenergized and closes a driving circuit from ground through sequence switch contact 359, the armature and front contact of relay 358 and the power 15 magnet of sequence switch 307 to ground, for moving this sequence switch out of position 13 into position 15. The ringing current is then disconnected from the line and the connection is completed through sequence switch contacts 360 and 361. The 20 supervisory relay SR' becomes energized.

When disconnection is desired and the calling and called subscribers restore their receivers, the two supervisory relays will be 25 actuated. The A operator causes the release of selector 115 in the same manner as was above described. Upon the release of the selector, relay 302 becomes deenergized and closes a circuit from ground through its 30 armature and back contact, a contact 362 of the power magnet of the sequence switch 307 to grounded battery, whereupon this sequence switch is moved out of position 15 and through position 17 into position 1. 35

40 When the sequence switch moves through position 17 and closes a contact 363, a lamp 364 is lighted, indicating to the B operator that the subscribers are through conversing. She removes plug 301 from jack 347, causing 45 thus the deenergization of relay 348 and the called subscriber's cut-off relay.

It will be obvious to those skilled in the art that instead of connecting the sender shown in Fig. 4 of the drawings directly to 50 a trunk, under the control of a cord finder switch, such sender will preferably be selectively associated with any one of a plurality of trunks assigned for use in a manner set forth in Patent No. 1,168,319 of January 18, 1916. The indicators shown in Fig. 3 may also be provided in common for a plurality of trunks, and will preferably be associated with a selected trunk under the control of 55 finder switches. Such an arrangement of 60 trunk finder switches is disclosed in my Patent No. 1,232,944, of July 10, 1917.

If the thousands digit of the called number is even and one of the No. 0, 2, 4, 6 or 8 thousands keys is depressed, then in position 65 8 of sequence switch 401 the translator

320 is moved to positions 0 or 1, because at the sender the circuit is closed through one of the hundreds keys in one row with key 424 which, as above stated, are wired to the No. 0 and No. 1 counting relays. In neither 70 of these positions of the translator 320 is contact 370 closed, and therefore when the tens indicator 310 closes its contact 334, no circuit will be found to cause the driving of the thousands indicator 308, and this indicator will be left in positions 0, 2, 4, 6 or 8, depending on which of the thousands keys was depressed. As it will be seen, the numerical designation of these positions correspond to the numerical designations of the 75 thousands keys. If, however, as in the above described case, an odd number thousands key (1, 3, 5, 7, or 9) is depressed, then in position 8 of sequence switch 401, the translator 320 is caused to move to positions 2 or 3, because the hundreds keys in one row with key 425 are wired to the No. 2 and No. 3 counting relays. In both these 80 positions of the translator, contact 370 is closed. In view of the fact that the left-hand contacts of the odd number thousands keys are wired to the same counting relays to which the even number thousands keys are wired, the thousands indicator stops in the same positions as in the aforementioned 85 case, when even number thousands keys were depressed. As soon, however, as the tens indicator closes contact 334, the circuit through the translator contact 370 and the thousands indicator contact 371 will be 90 established, and the thousands indicator will be moved out of the even position into the next odd position which is of the same numerical designation as the depressed odd 95 thousands key.

If an even or odd number thousands key is depressed and the hundreds digit is 0, 1, 2, 3 or 4, then in position 8 of the sequence switch 401, the translator 320 sends back one impulse or three impulses and is thus 100 moved into positions 0, or 2. In these positions of the translator contact 335 is left open, and for this reason the hundreds indicator will not be driven out of the position 105 into which it moved under the control of the sender.

Contact 327 of the hundreds indicator is closed in positions N-1/2, 5-1/2, 7-1/2 and 8-1/2. For this reason if the 0 hundreds key is depressed, the hundreds indicator 110 moves into position 0 and stops here, because contact 335 of the translator is not closed. If the No. 1 hundreds key is depressed the hundreds indicator is permitted to send back two impulses, one in position N-1/2 and the other in position 5-1/2 and 115 stops in position 1. If the No. 2 hundreds key is depressed the hundreds indicator sends back three impulses and stops in position 2, if the No. 3 hundreds key is de- 120

125

130

pressed then the hundreds indicator sends back four impulses and stops in position 3, and if the No. 4 hundreds key is depressed the hundreds indicator sends back five impulses and stops in position 4.

If the number of the depressed thousands key is even or odd and the No. 5, 6, 7, 8 or 9 hundreds key is depressed, then the translator is permitted to send back four or two impulses and will thus stop in positions 3 or 1. In these positions contact 335 is closed. The hundreds indicator will stop in the same positions as above indicated, but as soon as the tens indicator closes contact 334, 15 the hundreds indicator will be moved to the next position indicated at the normal contact 326 of the hundreds indicator; that is to say, into positions 5, 6, 7 or 9, depending upon which of the hundreds keys 5 to 9 was 20 depressed.

What is claimed is:

1. In combination, two selectively operable switching devices, a variably operable controlling device for said switching devices, means for adjusting said controlling device in accordance with a certain system of numerical designation, means responsive to the adjustment of said controlling device for operating one of said switching devices 25 in accordance with another system of numerical designation, and means responsive to the adjustment of said controlling device for operating the other one of said switching devices in accordance with the first mentioned system of numerical designation.

2. In combination, two selectively operable switching devices, a variably operable controlling device for said switching devices, means for setting the controlling device 40 in accordance with the decimal numerical system of designation, means responsive to the setting of said controlling device for operating one of said switching devices in accordance with a system of numerical designation other than the decimal 45 system, and means also responsive to the setting of said controlling device for operating the other of said selectively operable switching devices in accordance with the 50 decimal numerical system of designation.

3. In combination, two selectively operable switching devices, a sender for controlling the operation of said switching devices, an actuating member for said sender, 55 means for associating said sender with either one of said switching devices, means operable whenever the sender is associated with one of the switching devices and in response to the operation of said actuating 60 member for controlling the movement of said switching device a distance predetermined by said actuating member, and means operable whenever the sender is associated with the other one of said switching devices, and responsive to the actuation of 65

said member for controlling the movement of said last mentioned switching device to another distance than predetermined by the actuating member.

4. In a telephone exchange system, a plurality of lines, means including a selector switch for establishing a connection between a calling and a called line, a sender comprising numbered actuating members, arranged for adjustment in accordance with 70 the number of the called line, means responsive to the adjustment of said actuating members for causing said selector to take a number of steps different from the numbers of the adjusted actuating members of said 75 sender, number indicators movable under the control of said sender, and means for permitting said number indicators to take a number of steps corresponding to the numbers of the adjusted actuating members. 80 85

5. In combination, two groups of switching devices, a variably operable sender for controlling the operation of said switching devices, means responsive to a certain adjustment of said sender for causing any one 90 of the switching devices of one of said groups to traverse a distance identified by a certain number of units of a numerical system of designation, and means responsive to said certain adjustment of the sender for 95 causing any of the switches of said second group to traverse a distance identified by a certain other number of units of said numerical system.

6. In combination, a selectively operable 100 switching device having positions indicated by odd and even numbers, a variably operable sender, a plurality of actuating members for said sender indicated by odd and even numbers corresponding to the indications of the positions of said switching device, means responsive to the operation of an even number actuating member of said sending device for moving said switching device to a position designated by a corresponding even number, means responsive to the operation of an odd number actuating member of the sending device for moving the switching device to a position designated by an even number next lowest to the 105 odd number designation of the operated actuating member, and means operative only when an odd number actuating member has been operated for advancing the switching device to the next highest even 110 number position. 115

7. In combination, a selectively operable switching device having positions indicated by numbers 0 to 9, both inclusive, a variably operable sender having two sets of actuating members numbered 0 to 9, both inclusive, means responsive to the operation of an actuating member of one set and to the operation of any one of the actuating members numbered 5 to 9, both inclusive, of the 120 125 130

- other set for moving said switching device into any one of the positions designated by numerals 0 to 4, both inclusive, and means operative only if the latter mentioned actuating members of the second set are operated for advancing the switching device to positions corresponding in numerical designation to the operated actuating members of the second set.
- 10 8. In combination, a selectively operable switching device having positions indicated by numbers 0 to 9, both inclusive, a sending device having actuating members numbered 0 to 9 both inclusive, means operative in response to the operation of any one of the actuating members numbered 0, 2, 4, 6 or 8,

for moving said switching device into positions 0, 2, 4, 6 or 8 respectively, means operative in response to the operation of any one of the actuating members numbered 1, 20 3, 5, 7 or 9, for moving said switching device into any one of the positions 0, 2, 4, 6 or 8, respectively, and means operative only when any one of the latter mentioned actuating members is depressed for moving said 25 switching device into any one of the positions 1, 3, 5, 7 or 9, respectively.

In witness whereof, I hereunto subscribe my name this 19th day of September, A. D., 1916.

ALBEN E. LUNDELL.
